UNITED STATES PATENT OFFICE.

EDWARD R. KNOWLES, OF NEW YORK, N. Y., ASSIGNOR TO MERCANTILE ADVERTISING COMPANY, A CORPORATION OF NEW YORK.

ELECTRIC SIGN.

1,193,563.

Specification of Letters Patent.

Patented Aug. 8, 1916.

Application filed March 1, 1913. Serial No. 751,459.

To all whom it may concern:

Be it known that I, EDWARD R. KNOWLES, a citizen of the United States, residing at New York, in the county of New York and 5 State of New York, have invented certain new and useful Improvements in Electric Signs, of which the following is a specification.

This invention relates to electric signs and 10 letters, the sign being of that type in which each letter has combined therewith a lamp to form a unit whereby any combination of units may be made according to the name, words, or combinations of names and words 15 desired.

The invention has for one of its objects to provide a sign of this character which can be made large or small, according to requirements, and one in which every part is inter- 20 changeable and readily renewable and wherein the construction is comparatively simple, inexpensive and durable.

Another object of the invention is the provision of a letter or character structure in 25 the form of a casing having at one or more sides the characters or letters to be illuminated by the incandescent lamp which is inclosed by the casing, the letters being readily removable for interchanging, and the letter 30 structure as a whole being readily removable from the incandescent lamp.

Another object of the invention is the provision of an improved, novel and simple lamp socket construction which forms a support for the letter device as well as a holder 35 for the incandescent lamp, said socket having connectors which interlock with the connectors of adjacent sockets for connecting the lamps in the circuits.

Another object of the invention is the employment of a simple and effective supporting frame or base in which the lamp and letter units are mounted.

With these and other objects in view, as 45 will appear as the description proceeds, the invention comprises the various novel features of construction and arrangement of parts which will be more fully described hereinafter and set forth with particularity 50 in the claims appended hereto.

In the drawings, which illustrate one embodiment of the invention, Figure 1 is an end view of the sign. Fig. 2 is a front view of a letter and lamp unit with portions of the

base or socket in section. Fig. 3 is a central 55 vertical section of a unit. Fig. 4 is a horizontal section of a unit. Fig. 5 is a front view of a letter element. Fig. 6 is a vertical section of the letter element. Fig. 7 is a side view of the frame for holding the letter and lamp units. Fig. 8 is a bottom plan view of the terminal connector block of the sign. Fig. 9 is a section of Fig. 8. Fig. 10 is a sectional view of a spacing connector block adapted to be inserted between words. 65 Fig. 11 is a front view of a sign consisting of a plurality of letter and lamp units mounted in the folding frame.

Similar reference characters are employed to designate corresponding parts throughout the views.

Referring to the drawings, A designates the letter section of a unit, and B, the socket or base piece of the lamp section, both sections comprising a unitary structure designed to be mounted in a carrier or frame C, which latter is of such length to accommodate one or more groups of units for spelling words.

The letter device A is of any desired design or structure, but in the present instance the same consists of a hollow rectangular frame or casing having its front and rear open to receive letter or other character elements 1 that are plates of glass or other 80 suitable material of such shape and size as to fill the open sides of the casing. The letters may be made as an outline 2, as shown in Figs. 2 and 5, with the rest of the letter element opaque, while the letter 2 itself is 90 translucent to permit the light to pass therethrough, or the letter element may be made plain, as shown in Fig. 11. The sides 3 of the letter casing are preferably solid and opaque, and the top 4 connects the two walls 95 3 at the top, while the bottom plate 5 connects them at the bottom, such bottom plate 5 having an opening 6 for receiving the lamp, and at the opening 6 is a downwardly-extending frusto-conical flange or neck 7 for 100 fitting around the upper end of the tapering socket or base piece B of the lamp. The top 4 of the casing has a ventilating opening 9 and a hood 10 under the opening. To form supports for the upper portions of the 105 letter elements 1, the top 4 has depending flanges 11 and cooperating with each flange is a helical spring 12 fastened at its ends

13 to the letter casing, the said spring passing horizontally across the outer face of the letter element 1 at the top. The bottom of each letter element is retained in place by 5 a spring catch or clip 14^a carried by the bottom 5 of the letter casing. In this manner, the letter elements are readily removable and interchanged without requiring the removal of the whole letter device A. 10 Of course, a letter device of this character can be employed with a letter element only on one side while the opposite side is open to allow the light to shine out, or the casing may be closed on three sides. The casing 15 is so proportioned as to be large enough to inclose the incandescent lamp bulb L.

The socket or base piece B is made of porcelain or other suitable insulating material and has, in the present instance, a rectangular base 14 and rising therefrom is the upwardly-tapering socket portion 8 in which is arranged the metal socket or contact piece 15 into which is fitted the contact base 16 of the lamp, and the central contact 17 20 of the lamp is adapted to engage a contact piece 18 in the bottom of the socket 8. These contacts 15 and 18 are fastened in place by screws 19 and 20, respectively, which pass into the chamber of the socket upwardly 25 from the grooves 21 and 22 in the bottom surface of the base 14 of the socket piece. Assuming that the connectors 27 and 26 are connected respectively with the positive and negative sides of the circuit, the path of 30 the current consisting of the connector 27, screw 20, contacts 18 and 17, lamp filament 25, contact base 16, contact socket 15, screw 19, and connector 26.

As a matter of fact, the wires of the supply circuit are not connected directly with the screws 19 and 20, as connectors 26 and 27 are connected respectively with said screws, which connectors are disposed in the grooves 21 and 22 that extend parallel to each other 40 from one end of the base 14 to the other. Each connector 26 or 27 consists of a narrow strip of copper or other suitable metal doubled centrally on itself and formed at one end into an eye 28 or headed stud, while 45 the extremities of the metal strip are bent into spring jaws 29 so shaped as to receive the headed stud or eye 28 of the connector of adjacent letter and lamp unit. The connectors are mounted in their respective slots 50 of the base piece with the jaws 29 disposed within the base piece, while the tongue portions or headed studs 28 project beyond the base piece at the end opposite from the jaws. The screws 19 and 20 serve as the sole means 55 for holding the connectors in place.

The casing or frame C in which the letter and lamp units are mounted is a channel-shaped structure 30 just wide enough to receive the rectangular bases 14 of the socket pieces. The sides 31 of the supporting frame

have inwardly-extending flanges 32, Fig. 2, which engage over the bases 14 of the socket pieces. In this manner, the letters are placed in the frame of holder 14 by being inserted into the latter from the ends. In 70 inserting the letter and lamp units, they are so arranged that the projecting extremities of the connectors of the units will extend in the same direction so that the said projecting extremities 28 of the connectors of each 75 unit will extend into the jaws 29 of the adjacent unit. The holding frame C is mounted in brackets or supports comprising legs 32^a and a U-shaped member 33 that embraces the body of the holder or frame C and 80 has inwardly-extending lugs 34 engaging over the upper edges of the holder or frame C. Any number of these brackets 33 may be employed for each casing, two being shown in the present instance, and the 85 holder or frame C is secured with respect to the brackets by set screws 34^a in the brackets which screw into engagement with the frame C. In connection with the sign, an end connector block D, Figs. 8, 9 and 11, is 90 employed, the said block being a rectangular porcelain or other body 35 having grooves 36 and 37 for the connectors 26^a and 27^a, and to these connectors are attached the positive and negative wires of the supply circuit, 95 as shown in Fig. 8, each connector being formed with spring jaws 29^a to engage the projecting headed studs of the connectors on the adjacent unit. Where it is desired to separate letters, a spacing connector block 100 E, such as is shown in Fig. 10, is employed, this block being substantially the same as the base 14 of a lamp socket piece, with the exception that the socket portion is absent, and in each spacing connector block is mounted 105 the usual connectors, only one being shown in the section.

In order that the letter devices A may be kept in proper relative position on the socket pieces B, that is, prevented from turning, 110 the neck 7 of each letter device has a notch 40 to engage a projection or equivalent means 41 on the socket piece.

From the foregoing description, taken in connection with the accompanying drawings, 115 the advantages of the construction and of the method of operation will be readily apparent to those skilled in the art to which the invention appertains, and while I have described the principle of operation of the 120 invention, together with the apparatus which I now consider to be the best embodiment thereof, I desire to have it understood that the apparatus shown is merely illustrative, and that such changes may be made 125 when desired as are within the scope of the claims appended hereto.

Having thus described the invention, what I claim as new, is:

1. A lamp and letter unit comprising a 130

- 5 rectangular base piece of insulation having a rising chambered projection forming a lamp socket, a lamp in the socket, a letter bearing structure inclosing the lamp and having a downwardly extending neck on its bottom fitting the exterior of the projection, and interlocking means on the projection and neck for preventing turning of the said structure.
- 10 2. A lamp and letter unit comprising a base piece consisting of a base having a rising upwardly tapering socket projection, a lamp carried thereby, and a letter bearing structure having a downwardly flaring neck fitting the upper portion of the said projection for supporting the structure in spaced relation above the base.
- 15 3. A lamp and letter unit for signs comprising a socket having a base provided with a plurality of grooves in its bottom, and opening into opposite sides of the base, and metallic connectors fastened in the respective grooves and each having an end projecting out of its groove.
- 20 4. A lamp and letter unit for signs comprising a socket having a base provided with a plurality of grooves in its bottom, and metallic connectors fastened in the respective grooves, each connector consisting of a strip doubled on itself with its extremities forming spring contact jaws and having its doubled portion formed into a contact plug
- 25 or tongue to engage the jaws of a connector of an adjacent unit.
- 30 5. A lamp and letter unit comprising a base and socket having contacts in the socket and provided in its bottom surface with grooves extending from one side to the other, connectors extending longitudinally in the grooves, with one end of each connector projecting out of the end of its groove and from the base and single fasteners between the connectors and the respective contacts.
- 35 6. The combination of a plurality of sockets, each having in its bottom grooves extending from one end to the other, connectors in the grooves, the connectors of one socket engaging those of adjacent sockets, and a channel-shaped support in which the bases of the sockets are seated and which serves to cover the grooves and connectors.
- 40 7. The combination of a plurality of sockets having rectangular bases, a channel-support in which the bases are assembled having flanges engaging over the bases, and connectors in the bottom of each base and arranged to engage with the connectors of adjacent sockets.
- 45 In testimony whereof I affix my signature in presence of two witnesses.
- 50 EDWARD R. KNOWLES.
